UNITED STATES PATENT OFFICE.

ERNEST J. DERAGON, OF WORCESTER, MASSACHUSETTS.

CLOTHES-HANGER.

1,366,526.

Specification of Letters Patent. Patented Jan. 25, 1921.

Application filed August 14, 1920. Serial No. 403,462.

To all whom it may concern:

Be it known that I, ERNEST J. DERAGON, a citizen of the United States, residing at Worcester, in the county of Worcester and 5 State of Massachusetts, have invented new and useful Improvements in Clothes-Hangers, of which the following is a specification.

This invention is an improvement on the type of clothes hanger disclosed by my Patent No. 1,153,677, dated September 14, 1915, 10 said hanger comprising a sheet metal body having its ends bent over to form forwardly projecting upper and lower flanges, each provided with a series of sockets, said body 15 having integral rearwardly projecting upper and lower angular arms struck up therefrom, each arm including a horizontal bearing portion and a vertical pintle portion, a series of two-armed wire frames bent at the 20 inner ends of the arms to form pintles which are journaled in said sockets, and a bracket 25 adapted for attachment to a support, and having forwardly projecting upper and lower apertured ears forming seats for said bearing portions and sockets for said pintle 30 portions, the holder being adapted to swing on the bracket to a position permitting the frames to be closely assembled side by side.

The object of the invention is to so improve the form of the said sheet metal body 35 and bracket as to greatly increase the strength and durability of the hanger, and securely support the said wire frames so that they will not be liable to sag under the weight of fabrics placed upon them.

The invention is embodied in the improvements which I will now proceed to describe and claim.

Of the accompanying drawings forming 40 a part of this specification,

Figure 1 is a top plan view of a hanger embodying the present invention.

Fig. 2 is a vertical section on line 2—2 of Fig. 1.

Fig. 3 is a perspective view of the bracket.

Fig. 4 is a perspective view of the sheet metal body.

Fig. 5 is a section on line 5—5 of Fig. 2.

The same reference characters indicate the 50 same parts in all of the figures.

In the drawings 12 represents an elongated sheet metal body, preferably of sheet steel, having its end portions bent to form forwardly projecting angular flanges, each 55 including spaced apart upper and lower flange members 13 and 14, and a member

connecting neck 15, the members 13 and 14 being provided with alined sockets 16.

The body 12 is provided with integral rearwardly projecting upper and lower angular arms, each including a horizontal bearing portion 17 and a vertical pintle portion 18. The arm pintle portions 18 are of concavo-convex form in cross section, so that each has an arcuate inner face. 60

The body 12 is pivotally supported when in use, by a bracket, preferably formed from a single blank of sheet metal, and including upper and lower bosses 19, and longitudinal ears 21, perforated at 22 to receive attaching screws, whereby the bracket may be secured to a wall, or other vertical support. The upper ends of the bosses 19 form seats for the horizontal arm portions 17, and the central portions of said bosses form elongated arcuate bearings for the arcuate inner faces of the pintle portions 18. 65

The holder includes a plurality of wire frames, similar to those disclosed by the above-mentioned patent. Each frame includes two parallel arms 24 and 25, a connecting neck 26, and elongated vertical arm pintles 27, formed by bending the ends of the arms 24 and 25. The length of the arm pintles 27 is such that each pintle is journaled in two alined sockets 16, in the angular flange members 13 and 14, so that the arm pintles are firmly supported, and cannot be inclined from their predetermined vertical positions. 70

The body 12 and the wire frames connected therewith, are detachably engaged with the bracket, as in the device of the above-mentioned patent. 75

The improved device is distinguished from the patented device by the angular end flanges composed of the members 13 and 14, and necks 15, the elongation of the wire frame pintles 27, the arcuate form of the inner faces of the arm pintle portions 18, and the elongated bracket bosses 19, having central arcuate faces conforming to the arcuate faces of the pintle portions 18. The bosses 19 and pintle portions 18, formed as shown and described, provide a strong and durable 80 pivotal connection between the body 12 and the bracket, permitting the body and wire frames to swing freely, and at the same time preventing any possibility of displacement of the body 12 from its predetermined vertical position. 85

The body 12 is preferably bent at its lon-

itudinal edges to provide longitudinal ears 12^a, which impart longitudinal stiffness to the body.

I claim:

- 5 A clothes hanger comprising an elongated sheet metal body having its end portions bent to form forwardly projecting angular flanges, each including spaced apart upper and lower flange members and a member-
10 connecting neck, said flange members being provided with aligned sockets, said body being provided with integral rearwardly projecting upper and lower angular arms including horizontal bearing portions and ver-
15 tical pintle portions having arcuate inner

faces, a series of two-armed wire frames, bent at the inner ends of the arms to form elongated arm pintles, which are journaled in the angular flange sockets, each arm pintle being journaled in two sockets, and a 20 bracket adapted for attachment to a support, and having forwardly projecting bosses, forming seats for the bearing portions of said angular arms, and elongated arcuate bearings for the arcuate inner faces 25 of the pintle portions of said arms.

In testimony whereof I have affixed my signature.

ERNEST J. DERAGON.
